UNITED STATES PATENT OFFICE.

MARY E. BONTE, OF CINCINNATI, OHIO.

DESIGN FOR A MEAT-TENDERER.

SPECIFICATION forming part of Design No. 25,841, dated July 28, 1896.

Application filed June 9, 1896. Serial No. 594,889. Term of patent 7 years.

To all whom it may concern:

Be it known that I, MARY E. BONTE, a citizen of the United States, residing at Cincinnati, in the county of Hamilton and State of Ohio, have invented and produced a new and original Design for a Meat-Tenderer; and I do declare the following to be a full, clear, and exact description of the same, reference being had to the accompanying drawings, forming a part thereof.

My invention relates to a new and original design for meat-tenderers; and it will be fully understood from the following description and claim, when taken in conjunction with the accompanying drawings, in which—

Figure 1 is a side elevation of a meat-tenderer, showing my design; and Fig. 2 is an end elevation of the same.

Referring by numeral to the said drawings, 1 indicates the body of the meat-tenderer. This body 1 is of a general rectangular form in outline, and it is curved in a concavo-convex manner in the direction of its length with its concave side uppermost, as shown in Fig. 1, and is curved in a like manner in the direction of its width, as shown in Fig. 2. This body 1 is provided with depending teeth 2; and these teeth, which are of a circular form in cross-section and have conical lower ends, are inclined laterally and downwardly from the under convex side of the body 1, as shown in Fig. 1.

3 indicates arms which are connected to and extend upwardly from the opposite ends of the body 1. These arms are diminished 35 in width from the body 1 upwardly to their upper ends 5, which are of circular form when viewed in end elevation, and their edges are convex, as illustrated in Fig. 2, from the body 1 to the said reduced portion 4. The said 40 arms 3 are straight when the device is viewed in side elevation, and their upper ends 5 are seen to be of an increased thickness and of truncated-cone shape.

6 indicates the handle of the tenderer, 45 which extends between the end portions 5 of the arms 3. This handle 6 is of a circular form in cross-section and is of a greater diameter at its middle than at its ends, as shown in Fig. 1, and is also of a greater diameter at 50 its middle than the end portions 5 of the arms 3, as shown in Fig. 2.

Having described my invention, what I claim, and desire to secure by Letters Patent, is—

The design for a meat-tenderer, as herein shown and described.

In testimony whereof I affix my signature in presence of two witnesses.

MARY E. BONTE.
